Primary Examiner — Eric Goodman*Assistant Examiner* — Jennifer Watkins(74) Attorney, Agent, or Firm — Ralph E. Smith(57) CLAIM

The ornamental design for an automobile exterior, as shown and described.

DESCRIPTION

FIG. 1 is a front perspective view of an automobile exterior showing our new design; and,

FIG. 2 is a front view thereof.

It will be understood that the broken lines shown in the drawings illustrate portions of the automobile exterior that form no part of claimed design.
